UNITED STATES PATENT OFFICE.

WILLIAM L. WAGNER AND FRANK WAGNER, OF CLEVELAND, OHIO.

DESIGN FOR A CANDELABRUM.

42,843.

Specification for Design.

Patented July 30, 1912.

Application filed March 18, 1912. Serial No. 684,626. Term of patent 7 years.

To all whom it may concern:

Be it known that we, WILLIAM L. WAGNER and FRANK WAGNER, both citizens of the United States, and residents of Cleveland, in the county of Cuyahoga and State of Ohio, have invented a new, original, and ornamental Design for Candelabra, of which the following is a specification, reference being had to the accompanying drawing, forming part thereof.

In the drawings, the figure illustrates an isometric view of the candelabrum showing the same to be of the mission type.

What we claim is:

The ornamental design for a candelabrum, as shown.

Signed at Cleveland in the county of Cuyahoga and State of Ohio this fifteenth day of March 1912.

WILLIAM L. WAGNER.
FRANK WAGNER.
